(57) **CLAIM**

The ornamental design for a clamp mount, as shown and described.

DESCRIPTION

FIG. 1 is a front and top perspective view of a clamp mount, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of portion 9 shown in FIG. 1; and,

FIG. 10 is an enlarged view of portion 10 shown in FIG. 2.

The broken lines in the figures illustrate portions of the clamp mount that form no part of the claimed design. The dash dot dash lines in FIGS. 1, 2, 9 and 10 are for the purpose of depicting the boundary lines of the enlarged views and form no part of the claimed design.
